UNITED STATES PATENT OFFICE.

HENRY H. LUNG, OF PHILADELPHIA, PENNSYLVANIA.

PLUMB AND LEVEL.

1,082,163.

Specification of Letters Patent.

Patented Dec. 23, 1913.

Application filed January 29, 1912. Serial No. 673,996.

To all whom it may concern:

Be it known that I, HENRY H. LUNG, a citizen of the United States, residing in the city and county of Philadelphia, State of Pennsylvania, have invented a new and useful Plumb and Level, of which the following is a specification.

My invention relates to an improvement in plumbs and levels and consists in forming the stock thereof of sections and providing means for locking them continuously of each other as one.

It consists further of novel means for adjusting and securing the spirit bottle or tube in the stock.

It consists further of protecting the bottle or tube from the effect of falls or blows that may result to the device.

It consists further of means for causing the bubble in the bottle or tube to be seen most distinctly.

It consists further of means for rendering the circumferential scribes on the bottle or tube by which the bubble is centered to be rendered more discernible.

It consists finally of details of construction as will be hereinafter set forth and definitely claimed.

The invention is satisfactorily illustrated in the accompanying drawing, but the important instrumentalities thereof may be varied, and so it is to be understood that the invention is not limited to the specific arrangement and organization shown and described.

Figure 1 represents a side elevation of a plumb and level embodying my invention. Fig. 2 represents a vertical section on an enlarged scale on line $x-x$. Fig. 1. Fig. 3 represents a side view of the central portion of the device on a further enlarged scale, certain members thereof having been removed. Fig. 4 represents a longitudinal section of said portion. Fig. 5 represents a transverse section on line $y-y$. Fig. 4. Fig. 6 represents a partial side elevation and a partial longitudinal section of an end portion of the device on an enlarged scale. Fig. 7 represents a perspective view of a detached portion of the device.

Similar letters of reference indicate corresponding parts in the figures.

Referring to the drawings:—A designates the stock of the device, the same being composed of sections B, C, D, which are provided respectively at their ends

with tongues E and grooves F forming dovetailed joints, the tongues of the respective sections entering the grooves of the adjacent sections, thus locking the sections as one and forming the stock of a continuous length comparatively intact, said sections, however, being adapted to be separated at their joints, and placed in small compass convenient for carrying, packing, storage, transportation, etc.

The walls of the members comprising the dovetailed joints are covered with facings G of metal or other suitable material secured thereto in any suitable manner, thus protecting said members from blows, and reinforcing or strengthening the same, thus adding to their durability and preventing any material injury to said members in assembling and disjointing the sections.

In the center of the stock is the recess H which is open on opposite sides of the same so as to expose the spirit containing bottles or tubes J which are located and secured therein, said bottles or tubes having each a bubble therein as usual in plumbs and levels, it being noticed that there are two such bottles or tubes, they being arranged parallel in said recess, the latter being separated or divided by tongues K which are inturned from the adjacent portions of the stock.

The top of one recess is formed by the wall L and the bottom of the other recess is formed by the wall M, it being noticed that said walls extend in the longitudinal direction of the stock, and are continuous with the adjacent portions of the same it being noticed also that each tube is fitted in its recess between one of the walls L or M and the opposite sides of the tongues K, it being noticed that the end portions of the recesses are of dovetailed form.

The tubes J are inclosed by outer tubes N whose ends are secured thereto by the caps P of plaster or cement, such as plaster of Paris, which is poured in plastic condition between the tubes. Cushions Q of resilient material are placed against the ends of the inner tubes and inclosed by said plaster. Packing rings R are interposed between the outer and inner tubes so as to encircle the inner tubes. By these means the tubes are not likely to be broken by end or side thrusts due to the falling of the device or blows imparted to the same when in use.

The plaster employed as above, when set, interlocks with the adjacent walls of the

stock about the recess H owing to the dove-tailed nature of said walls and so the plaster cannot escape from the stock either at the usual viewing opening A' in one side of the 5 stock, nor through the viewing opening A² in the other side of the stock made in the ring A³, which closes the recess H, the bubbles in the spirit of the tubes being centered at said openings.

10 In order to adjust the tubes in the recess, I employ the longitudinally-extending wedges S which are driven into the spaces between the outer tubes N and the tongues K and transversely-extending wedges T 15 which are driven into the spaces between said tubes and the walls L, M, said wedges tightening against the tubes, firmly seating them and serving also primarily to adjust said tubes to be truly horizontal in the stock 20 by the extent to which the wedges are driven into position.

Interposed between the inner and outer tubes are the sheets or plates U of paper or other material which encircle portions of the 25 inner tubes in the longitudinal section thereof opposite to the locations of the bubbles when the device is in use. This forms a contrast with the glare or shine of said tubes and comparatively removes the same from 30 the tubes in viewing said bubbles and so the latter are more perceptible in viewing. In order to hold said sheets or plates in position, I employ the threads V which are wound around the same and also around the 35 tubes J and knotted or otherwise secured, see Fig. 7, said threads also occupying the usual scribes V' in said tubes J so as to be prevented from shifting and serving also by their contrasting color to make the centering 40 of the bubbles in the tubes between said scribes more apparent to the observer and so more easily read-off by the latter. Tubes

or bottles W are inserted in openings in the ends of the stock and retained in place by the plaster X and plugs Y.

It will be noticed that the tubes are duplicated at the center and the ends of the stock, so that either side or end of the latter may be used for the level or plumb and the stock has a scribe Z centrally in the length thereof 50 for the use of the plumb line.

Having thus described my invention what I claim as new and desire to secure by Letters Patent, is:—

1. In a plumb and level, a stock, a spirit 55 tube therein, a scribe on said tube, a piece of contrasting material partially around said tube in the longitudinal direction thereof opposite the bubble when in use and threads encircling said piece and tube to retain the 60 piece in position, said scribe being disposed to center the bubble and having said threads seated therein.

2. In a plumb and level, a stock having a recess therein, a spirit tube in said recess, an 65 outer tube, wedges interposed between said outer tube and the adjacent wall of the recess to adjust said tube in the recess, and filling in said recess around the ends of the spirit tube, said wedges controlling said outer tube 70 in its adjustment.

3. In a plumb and level, a stock having a recess therein, a spirit tube in the same, said recess being of dove-tailed form, plaster filling said recess and inclosing the ends of 75 said tube, an outer tube inclosing said spirit tube, and wedges interposed between the ends of the outer tube and the adjacent plaster and extending lengthwise of the tube to adjust the latter in the recess.

HENRY H. LUNG.
